UNDERREAMER

Fred Swan, Wichita, Kans.

Application November 25, 1936, Serial No. 112,767

12 Claims. (Cl. 255—76)

The present invention consists of an underreamer especially adapted for use in oil wells and is an improvement on patents previously granted to me in this art, especially my Patents Numbers 5 1,372,917 and 1,578,482, as well as Swan Patent No. 997,718. While the Swan underreamers, now extensively used in this art, are effective for reaming a hole of greater diameter than the interior of the casing regardless of the strata 10 formation of the earth, I have found that a more efficient tool is provided by following the teaching of the present invention, a preferred form of which is illustrated in the accompanying drawings.

15 It is within the contemplation of this invention to retain cutters operated into an expansive or operating position by an upwardly moving spring rod but the mounting of the cutters has been modified to change the angularity of the cutters 20 when in use to positively effect operation of the cutters through any of the variety of earth formation, whether hard or soft, with minimum wear on the tool and with a complete elimination of tool fracture, rupture or breakage, notwithstanding the fact that the working ends of 25 the cutter may impinge against solid formation immediately on leaving the casing, the angularity of the cutters positively preventing their collapse when engaged with rock or like solid formations.

30 It is a further object of this invention to provide expandible cutters, the work engaging terminals of which are free to permit contact of the complete terminals with the work, the conformation of the terminals and the angularity of cutter 35 bodies permitting the wall to be attacked from above, after initial penetration of the wall surface, as well as at the side to more expeditiously and more effectively break down the wall, during which operation the line of stress is on the 40 long axes of the cutters.

Another object of the invention is to provide a cross bar which is automatic in its operation to lock the spring rod and cutters together when the cutters are moved into an expanded position, 45 the bar being loosely mounted in the spring rod and cutters and being freely removable when the cutters are in a collapsed position. It is also within the contemplation of the present invention to provide a detent, which is also automatic in its operation, to secure the cutters in a collapsed position, the detent being likewise automatically disengaged when the reamer is operated to permit the cutters to expand, the detent 50 being of peculiar design to assure its effective

operation over a long period of time without replacement.

Other objects of the invention will be apparent from the following description of the present preferred form of the invention, wherein:—

Fig. 1 is a vertical sectional view of an underreamer constructed in accordance with the present invention illustrating its application, showing the cutters in an expanded or operative position.

Fig. 2 is a similar view showing the cutters in a collapsed position within the confines of the casing.

Fig. 3 is a fragmentary detail enlarged view of the reamer body showing the spring rod and 15 detent in side elevation illustrating the manner in which the rod is held in a fixed position by the detent.

Fig. 4 is a detail fragmentary perspective view of one of the detents.

Fig. 5 is a side elevational view, partly in section, of a reamer body constructed in accordance with this invention.

Fig. 6 is an end elevational view of one of the cutters.

Fig. 7 is a fragmentary elevational view of the reamer body showing the cutters mounted therein, the latter being in collapsed position.

Fig. 8 is a side elevational view of one of the cutters.

Fig. 9 is an elevational view of the spring rod constructed in accordance with the present invention.

Fig. 10 is a side elevational view of an underreamer constructed in accordance with this invention showing the means of the present invention used for collapsing the cutters.

Fig. 11 is a perspective view of the locking bar, and

Fig. 12 is a cross sectional view shown on the 40 line 12—12 of Fig. 10, looking in the direction of the arrows, illustrating the manner of mounting the releasing bar through the reamer body, above the spring rod.

In the drawings for purpose of illustration, a 45 portion of a well casing 13 is shown which is of standard construction, and is mounted in the earth in a manner well known in the art.

The tool constructed in accordance with the present invention includes a reamer body 14, the 50 lower terminal of which is provided with recesses 15 in the sides thereof, the portions of the terminals below said recesses being rounded, as indicated at 16. The inner wall of each of the terminals 16 is rabbeted out to provide cutter 55

engaging recesses 17. The reamer body 14 is provided with the usual bore 18, which is constricted, as indicated at 19, just above the rounded terminal 16. The wall of the reamer body is provided with longitudinal slots 20 in the opposite sides of the body, the slots being preferably formed at a point appreciably above the constricted bore 19.

Mounted for movement in the bore 18 is a spring rod 21, the upper end of which is formed to provide a head 22 in which a kerf 23 is formed. The lower end 24 of the rod is enlarged, the jointure of the rod proper and the enlargement being formed to provide bevelled shoulders 25. The lower end of the enlargement 24 is tapered to provide a truncated cone shape terminal 26. The enlarged end 24 of the rod is provided with a longitudinal slot 27 which is adapted for the reception of a cross bar 28, the free ends of which project beyond the rod and engage complementary openings 29 formed in cutters 30. Preferably, the cross bar 28 is of the configuration shown in Fig. 11 of the drawings and includes flared terminals 31. This contour of cross bar permits the latter to be freely engaged with and disengaged from the cutters and spring rod. However, when the cutters 30 are in an expanded position, as shown in Fig. 1 of the drawings, the inclined free faces of the flared ends 31 bear against the correspondingly formed upper walls of the openings 29 of the cutters, while the lower faces of said flared ends bear against the lower walls of the cutters thereby positively locking the cutters from displacement and also preventing the cross bar from any appreciable longitudinal movement of the cross bar. If perchance the cross bar should move lengthwise, in either direction during the operation of the tool, the conformation of the flared ends and the walls of the cutters automatically returns the cross bar to a central or normal position, as shown in Fig. 1.

Each of the cutters 30 is provided at its upper or inner end with a boss 32 which complements and is movably engaged in one of the recesses 17 in the lower terminal of the reamer body. The upper or inner wall of each cutter is formed to provide an abrupt shoulder 33 which complements and is adapted for engagement in one of the recesses 15. By this formation the support of each cutter when in the expanded position shown in Fig. 1 of the drawings is on the line of impact of the cutter, the line of impact carrying substantially through the top of the axis of the cutter and the solid walls of the reamer body 55 at diametrically opposite points. By this construction, excessive outward or expansive movement of the cutters is prevented, yet the free ends of the cutters are in no way restrained or housed leaving them free for engagement with the work. Preferably, the working terminal of the cutter is of substantially inverted V-shape configuration, as indicated at 34, it being preferred to slightly elongate the inner or trailing toothed portion of each cutter. The outer or entering toothed portion of each cutter, which is relatively shorter, is adapted for penetration in the wall, but is operated so as to first bite into the wall surface and then tear down the sub-strata of earth regardless of its formation. The inner or trailing tooth of each cutter serves as a guide and as shown in Fig. 1 of the drawings normally remains slightly spaced from the wall being torn down.

In order to expand the cutters 30, as shown in Fig. 1 of the drawings, I provide the rod 21 with a spring 35, one end of the spring bearing against

the head 22 while the opposite end bears against a permanent part of the reamer body just above the constricted portion 19 of the bore. Consequently pressure is exerted upwardly on the rod 21 which correspondingly urges the cross bar 28 upwardly and throws the lower or working ends of the cutters outwardly into expanded position. This angularity of the cutters positively insures engagement of the outer toothed portions of the cutters with the wall and likewise prevents casual folding or collapsing of the cutters when solid formations are encountered during the reaming operation.

While the reamer is being passed through the casing, it is desired that the cutters be held in a collapsed or inoperative position and for this purpose I provide a detent 36 which is mounted through the wall of the reamer body and is adapted for engagement with one of the bevelled shoulders 25 of the rod. Preferably, the rod 20 engaging end of the detent is squared to provide a plurality of flat faces 37, each of which is bevelled to conform to the contour of the shoulders 25 and anyone of which may be engaged with said shoulders. Consequently, as one of the square faces of the detent wears, the detent may be rotated to bring another face into use. Correspondingly, when one of the shoulders 25 begins to show wear, the rod 21 may be turned so as to bring the other shoulder into play. The detent 30 is provided on its outer end with a head 38 which serves as an abutment for one end of a spring 39, the upper end of the spring bearing against the reamer body around the opening in the latter through which the detent moves. Consequently 35 the detent is normally held disengaged from the rod 21. When the detent is in a disengaged position, it is retained from displacement by a screw cap 40 mounted in the reamer body outside of the detent head 38. When it is desired to collapse the cutter heads, downward pressure is exerted on the rod 21 in a manner hereinafter set forth, and at the same time pressure is placed on the head 38 of the detent by a suitable implement. As soon as the rod 21 has been depressed 45 to the point where one of the shoulders 25 crosses said detent, the latter will automatically move into position above the shoulder as shown in Fig. 3. By releasing pressure on the rod 21 the detent and rod are frictionally locked in an apparent manner. When in a collapsed position the cross bar 28 is free to be engaged with or disengaged from the cutters and spring rod. To prevent accidental displacement of the cross bar while the tool is being passed through the casing, 50 I provide the cutter heads with grooves 41 and the flared ends of the cross head 28 with openings which are adapted for engagement by a strand of wire 41'. The wire is secured and this is sufficient to hold the cutter heads against the 55 lower end of the spring rod, as well as preventing the cross bar 28 from displacement. As soon as the lower end of the tool leaves the casing and it is desired to expand the cutters, contact is made with the tool in the usual manner, the impact of which is sufficient to move the rod 21 slightly downwardly which causes automatic release of the detent 36 thereby permitting the cutters to break the strand of wire surrounding the same and to expand into operative position. 60

A preferred form of means of depressing the rod 21, which is commonly referred to in field work as a "pull down", is illustrated in Figs. 10 and 12 of the drawings. This depressing means or "pull down" includes a bar 42, which is adapt- 75

ed to be engaged through the slots 20 of the reamer body and with the kerf 23 of the spring rod 21. One of the bars is engaged through a link with one end of a U-shaped frame 43, the upper end of said frame being engaged with a recess 44 formed in the upper margin of the bar 42. The U-shaped frame extends appreciably below the tool and is adapted to be engaged by a chain or other suitable means 45 anchored to a support. When the tool is elevated by hoisting means commonly employed in the art, the spring rod is caused to be depressed against the resistance of the spring 35 until the detent 36 locks over one of the shoulders 25 in a manner already described. Following this operation the depressing means or "pull down" may be disengaged in an apparent manner.

While I have herein described a preferred form of the invention which I have found in actual practice to perform the functions attributed to it, I am nevertheless aware that various changes may be made therein within the scope of the claims herewith appended.

What is claimed is:

1. An underreamer for oil wells including a reamer body equipped with cutters one end of each of which is pivotally mounted in a terminal of the body and movable to project the free ends of the cutters outwardly beyond the plane of the reamer body and completely below the terminal of said body, the reamer body engaging ends of the cutters having abrupt shoulders for engagement in complementary recesses formed in the reamer body, said recesses being formed in the body in a plane above the pivotal axes of the cutters and being disposed on such an inclination from the horizontal as to provide cutter supports in the direction of the normal thrust of the cutters.

2. An underreamer for oil wells including a reamer body equipped with cutters pivotally mounted in the lowest terminal of the body, the cutters being movable to permit expansion of their free ends outwardly at an angle to the body axis, the upper ends of the cutters engaging the lower terminal of the reamer body above the pivotal axes of the cutters in a plane normal to the cutter angle, whereby impact on the latter will be absorbed by the central portion of the reamer body in the direction of the normal thrust.

3. An underreamer for wells including a reamer body equipped with cutters pivotally mounted in its lowest end, the work engaging terminal of each of which is of substantially inverted V-shape to provide a pair of obtusely related teeth, said cutters being expandable to dispose said teeth at an angle oblique to the longitudinal axis of the reamer body whereby one tooth of each cutter is disposed substantially entirely within the unreamed hole and is permitted to penetrate the work in advance of the other tooth, said one tooth constituting a guide tooth disposed on an oblique angle to the wall of the unreamed hole, and said other tooth being disposed substantially entirely outside of the unreamed hole.

4. An underreamer for wells including a reamer body, cutters pivotally mounted in said body, means mounted in said body for expanding the cutters including a spring rod and a cross bar, said cross bar being loosely mounted in the spring rod and cutters and removable therefrom when the cutters are collapsed, the cross bar having end portions so shaped as to automati-

cally lock the cutters from displacement when in expanded position.

5. An underreamer for wells including a reamer body provided with opposed longitudinal slots, cutters mounted in said body, means mounted in said body for expanding the cutters including a spring rod provided with a slotted head, and means engageable in said slots for depressing said rod to collapse the cutters including a bar engageable through the reamer body and in the slotted head and downwardly urged pressure exerting means engaged with the ends of said bar.

6. An underreamer for wells including a reamer body, cutters pivotally mounted in said body the outer faces of which are grooved, means for expanding the cutters including a spring rod and a cross bar, said cross bar being loosely mounted in the spring rod and cutters and removable therefrom when the cutters are collapsed, the ends of said bar being perforated in the plane of the cutter grooves, and means engageable through said perforations and with said grooves to prevent displacement of said bar and the cutters when the latter are collapsed.

7. An underreamer for wells including a reamer body provided with opposed longitudinal slots, a pair of cutters pivotally mounted in an end of said body and provided with opposed openings, a spring-pressed rod slidable in said body provided with an opening adjacent the lower end thereof, a bar loosely disposed in said openings of said cutters and the opening in said rod, a head on the upper end of said rod, and means engageable with said head through said slots to move said cutters to collapsed position.

8. An underreamer for wells including a reamer body provided with opposed longitudinal slots, a pair of cutters pivotally mounted in an end of said body and provided with opposed openings, a spring-pressed rod slidable in said body provided with an opening adjacent the lower end thereof, a shoulder carried by said rod intermediate the ends thereof, a spring-pressed detent carried by said body and engageable with said shoulder for holding the cutters in collapsed position, and means engageable with said rod through said slots in said body for moving said cutters to collapsed position.

9. An underreamer for wells including a reamer body, a pair of cutters pivotally mounted in an end of said body provided with grooves in the outer surfaces thereof, spring-pressed means carried by said body engaging said cutters for moving said cutters to extended position, and frangible means engageable in said grooves for holding said cutters in collapsed position.

10. An underreamer for wells including a reamer body, a pair of cutters pivotally mounted in an end of said body provided with grooves in the outer surfaces thereof, a bar loosely engaging said cutters and disposed transversely of said body, spring-pressed means carried by said body engaging said bar for moving said cutters to extended position, said bar having a notch in each end thereof adapted to align with the grooves in said cutters, and frangible means engageable in said grooves and said notches for holding said cutters in collapsed position while simultaneously holding said bar from lateral movement relative to said cutters when said cutters are in collapsed position.

11. An underreamer for wells including a reamer body, cutters pivotally mounted in said body the outer faces of which are grooved, means

for expanding the cutters including a spring rod and a cross bar, said cross bar being loosely mounted in the spring rod and cutters and removable therefrom when the cutters are collapsed, the ends of said bar being perforated in the plane of the cutter grooves, and frangible means engageable through said perforations and with said grooves to prevent displacement of said bar and the cutters until the latter are expanded.

12. An underreamer for wells including a reamer body, cutters mounted in said body the outer faces of which cutters are grooved, means carried by said body for expanding the cutters, and frangible means engageable through said first means and with the cutter grooves to prevent displacement of said first means and cutters until the latter are expanded. 5

FRED SWAN.
